UNITED STATES PATENT OFFICE

JOHN H. SHAW, OF NEW HAVEN, CONNECTICUT, ASSIGNOR TO SARGENT & COMPANY,
OF NEW HAVEN, CONNECTICUT

PADLOCK

Application filed June 20, 1930. Serial No. 462,626.

My invention relates to a padlock, and the general object of the invention is to bring about a compact and relatively simple form of padlock in which the locking mechanism is secured against unauthorized tampering.

A further object of the invention is to bring about a form of padlock having a frame or body in which the locking mechanism may be inserted as a unit.

10 A feature of the invention resides in a relatively simple form of locking bolt and locking mechanism so arranged that they mutually support one another within the padlock casing.

15 To these and other ends, the invention consists in the novel features and combination of parts to be hereinafter described and claimed.

In the drawing:

20 Fig. 1 is a side elevation of a padlock according to my invention, opened up to show the interior construction;

Fig. 2 is a view similar to Fig. 1 but in section;

25 Fig. 3 is a view along line 3—3 of Fig. 1; Fig. 4 is a view along line 4—4 of Fig. 1, and

30 Fig. 5 is a view showing the parts of the padlock during the process of assembling the same.

Referring to the drawing in which I have illustrated my invention by showing a preferred embodiment of the same, the reference numeral 10 indicates in general the improved padlock which comprises a casing 11, provided with a generally square transversely extending opening 12, adapted to receive therein the locking mechanism in a manner to be hereinafter described, and parallel bores 13 and 14 at the opposite sides of the opening 12 in which the legs 15 and 16 of shackle 17, are received. The leg 15 is relatively longer than leg 16 and is reduced at its lower end 18 for the reception of compression spring 19, the lower end of which bears against the casing 11 at the bottom of bore 13.

Mounted in the upper end of opening 12 is a locking dog or bolt 20, having a cylindrical stud 21 received in an opening 22, in frame

11, the ends 23 and 24 of bolt 20 being received in notches 25 and 26 in legs 15 and 16, when the shackle is locked to the casing.

Within the opening 12, between bolt 20 and the lower end of the opening, is a locking mechanism, in this instance a pin tumbler mechanism, generally designated by the reference numeral 27, and comprising a shell 28 having a bore 29 in which a key plug 30 is mounted, key plug 30 having at its lower end a generally cylindrical extension 31, which is received in opening 32, in the lower end of casing 11. Upon the upper end of plug 30 is a roll-back 33, having a talon 34, which engages bolt 20 to rotate the latter about stud 21 as a center to disengage the ends 23 and 24 from notches 25 and 26, whereupon the shackle 17 moves outwardly from casing 11 under the urge of spring 19, outward movement of shackle 17 being limited by lug 35 on shell 28, which rides in a mill cut 36, in leg 15, and engages a shoulder 37 at the lower end of the cut. Adjacent the shoulder 37, the leg 15 is provided with an annular groove 38 in which the lug 35 is received if the shackle 17 is rotated about the axis of leg 15 when fully opened, the shackle being otherwise limited to movement axially of leg 15 by lug 35 cooperating with the bottom of mill cut 36.

At either side of casing 11 and closing the opening 12 are plates 39 and 40, which serve to hold the parts of the locking mechanism within the casing 11, the bolt 20 being constantly urged into locked position by spring 41, one end of which is fixedly mounted in slot 42, in bolt 20, while the other end bears against plate 40. Movement of bolt 20 is limited by shoulders 43 and 44, which engage plate 40 at the limits of movement of the bolt.

At the lower end of opening 12 and above opening 32, the casing 11 is transversely slotted as at 45, the depth of the slot being substantially equal to the thickness of bolt 20.

In assembling the padlock, the leg 15 of shackle 17 is inserted in opening 13, with the spring 19 mounted on the reduced end 18. The locking mechanism 27 is inserted in opening 12 until the cylindrical portion 31

of shell 28 is opposite the opening 32, whereupon the locking mechanism may be moved downwardly into the position shown by Fig. 5 of the drawing. The bolt 20 is then assembled on the upper face of roll-back 33 in the position shown in Fig. 5, whereupon the locking mechanism, together with the bolt, may be moved upwardly to bring stud 21 into opening 22. The shackle is then forced inwardly into the casing 11 and the locking mechanism and bolt rotated into the position shown in Fig. 1 of the drawing, whereupon the plates 39 and 40 may be assembled on the sides of the casing 11. The plates 39 and 40 may be secured to casing 11 in any preferred manner, in the present instance the edges of the plates being chamfered as shown in Figs. 3 and 4, and the edge portions of the casing 11 bent around the chamfered edges of the plates to hold the latter against detachment from the casing. Alternately the parts of the lock may be assembled by first assembling the bolt member 20 within the lock case in its operative position as shown in Fig. 2. The lock mechanism 27 may then be tipped slightly and the end of the key barrel 31 inserted in the opening 32, after which the body of the lock mechanism may be moved to the position shown in Fig. 5 about the key barrel as a pivot, then by raising the shell 28 so as to clear the shoulder 49, the lock mechanism may be rotated to operative position as shown in Fig. 1.

The shell 28 is of such thickness that it contacts with plates 39 and 40, as shown in Fig. 3 of the drawing, and is provided with ribs 46 and 46^a adjacent to lug 35, ribs 46 and 46^a engaging the inner faces of plates 39 and 40 to assist in holding the locking mechanism against movement within the casing. The ends 23 and 24 of dog 20, are provided with semi-circular portions 47 and 48, which engage the shackle when the same is unlocked to hold the bolt in unlocked position.

While I have shown and described a preferred embodiment of my invention, it will be understood that it is not to be limited to the details shown, but is capable of modification and variation within the spirit of the invention and scope of the appended claims.

What I claim is:

1. In a padlock, a casing having an opening therein, a key operated mechanism and a bolt mounted between the opposite ends of said opening, and a transverse cut in said casing at one end of the opening, the distance between the bottom of the transverse cut and the opposite end of the opening being at least equal to the length of the key operated means.

2. In a padlock, a casing having a transversely extending opening, a key operated mechanism having a cylindrical extension, said casing also having a cylindrical recess facing into the transverse opening, in which

said extension is received, the distance between the side of the transverse opening adjacent said cylindrical recess and the opposite side of the transverse opening being at least equal to the total length of the key operated mechanism. 70

3. In a padlock, a casing having a generally transverse opening therein provided with opposite faces, a bolt pivotally seated on one of the faces of said opening and presenting a relatively flat face towards the opposite face of the opening, a key operated mechanism mounted in and fitting the space between the flat face of the bolt and the opposite face of the opening to hold the bolt against movement away from its seat, and said casing being provided with a recess into which the key operated mechanism may be moved in a direction away from said bolt to free the latter for movement away from its seat and out of the lock casing. 75 80 85

4. In a padlock, a casing having a generally transversely directed opening therein provided with opposite faces, a bolt pivotally seated on one of the faces of said opening and presenting a relatively flat face towards the opposite face of the opening, a key operated mechanism mounted in and fitting the space between the flat face of the bolt and the opposite face of the opening to hold the bolt against movement away from its seat, and said casing being provided with a recess into which the key operated mechanism may be moved upon rotation thereof, the key operated mechanism being moved into said recess 90 95 100 in a direction away from said bolt to free the latter for movement away from its seat.

5. In a padlock, a casing having a generally transversely directed opening therein provided with opposite faces, a bolt, and a key operated mechanism for said bolt mounted between the opposite faces of the opening and mutually supporting one another in the casing, said casing being provided with a recess into which one of said mutually supporting devices may be moved to free the other thereof for movement into and out of said casing. 105 110

6. In a padlock, a casing having a generally transversely directed opening therein provided with opposite faces, a bolt, and a key operated mechanism for said bolt mounted between the opposite faces of the opening and mutually supporting one another in the casing, said casing being provided with a recess into which one of said mutually supporting devices may be moved upon rotation thereof to free the other thereof for movement into and out of said casing. 115 120 125

7. In a padlock, a casing having a transversely directed opening therein provided with opposite faces each of which is intersected by a recess, a bolt seated on one of said faces and having a stud in the recess therein, a key operated mechanism seated between said bolt and the opposite face and having 130 135

a stem extending into the recess in the opposite face, and said casing being provided with a third recess into which one of these devices may be moved to free the other for movement out of the lock casing.

- 5 8. In a padlock, a casing, a shackle mounted on said casing, and means for locking said shackle against movement with respect to said casing, said casing being provided with an opening having opposite faces, each of
10 which is provided with a cylindrical recess opening therein, said locking means for said shackle comprising a bolt seated against one of said faces and having a stud extending into the recess opening thereinto, and a key operated mechanism mounted in and fitting the space between the bolt and the other of said faces, said mechanism having a stem extending into the recess opening into the last named face, and said casing being provided with a
15 third recess into which one of said devices may be moved to free the other thereof for movement into and out of the lock casing.
- 20

In witness whereof, I have hereunto set my hand this 17 day of June, 1930.
